RAILWAY CAR TRUCK SPRING

Thomas H. Symington, Baltimore, Md., assignor
to T. H. Symington & Son, Inc., Baltimore, Md.,
a corporation of Maryland

Application June 18, 1931. Serial No. 545,336

11 Claims. (Cl. 267—4)

The invention relates to railway car truck springs and has special reference to that type located within the window openings of the side frames for the purpose of yieldably supporting 5 the bolster and of course the load thereon.

The principal object of the invention, generally stated, is to provide a spring construction and combination based upon the ideal spring curve which is calculated to be gradual or comparatively flat at the beginning of the travel and to be increasingly abrupt along a series of successive steps, the plurality of breaks in the direction of the curve corresponding to and being indicative of the spring action under different 15 load conditions and at different points in the travel.

Whenever a truck bolster is supported upon springs of any standard type, it has been found that there is always a certain tendency of the 20 springs to vibrate vertically or "jiggle". When this movement builds up the effect on the car, and its lading, particularly in the case of perishable goods, is most injurious. This vertical jiggle develops to its maximum extent when the 25 natural period of vibration of the springs coincides with the frequency of the jolts or impulses caused by passage of the car wheels over the rail joints. When this synchronization occurs, which it is bound to do at certain critical car 30 speeds, the situation becomes really alarming, thus necessitating that steps be taken to check it. When the speed is accelerated or decelerated so as to break up this synchronization the vertical jiggle is checked but, unfortunately, in the 35 case of long or solid trains the rate of acceleration or deceleration is comparatively slow so that this destructive jiggle may continue for a considerable length of time, for instance while the train is travelling a mile or even considerably 40 more which it must do before the speed will change sufficiently from the critical speed to effect any appreciable checking.

The exact behavior of springs of different types varies and it has been found by actual test that 45 the critical speed for an A. R. A. spring is thirty-three miles per hour and for the Norfolk and Western type is thirty-eight miles per hour. When the load on such springs is plotted against the travel the working curves of the two types 50 subtend an angle of about eighteen degrees corresponding to a change in the critical speed of five miles as mentioned above. If while a car is travelling and reaches the critical speed it were feasible to replace one type of springs with another it is quite apparent that the tendency to

vertical jiggle would be checked. Of course such would be a physical impossibility and it would therefore be necessary to adopt an arrangement and construction wherein use is made of springs which will perform differently under different 60 conditions so that the objectionable vibratory movement will be checked.

It is with all of the above facts in view that I have devised the present invention which contemplates the provision of a truck spring assembly 65 based on the ideal curve, as mentioned hereinbefore, and which embodies a plurality of units, certain of which are effective under all loads and others of which will come into play either when the load is increased or when certain of the 70 units have been depressed to a certain predetermined travel, it being an important feature that the various springs have different natural periods of vibration so that the working curve of the entire assembly will be stepped or broken at intervals.

Another object of the invention is to provide a spring assembly having a stepped or broken working curve and in which the arrangement is such that at different positions or decrease of 80 loading the spring will start to vibrate at the natural critical speed of that portion of the curve and will continue to vibrate until the movement rides into the angular curve either above or below the particular loaded position, the theory being 85 that at this new portion of the curve there will be a different critical speed so that the effect will be to break up the car jiggle without any noticeable shocks within the car.

A more specific object of the invention is to 90 provide a truck spring assembly in which there is a soft spring resistance to light load gradually increasing step by step by either a uniform or varying increment until a certain predetermined load limit is reached, after which the resistance 95 or capacity is materially increased and maintained substantially constant in successive steps.

Another important object is to provide a spring assembly including a plurality of units certain of 100 which have different deflection rates at different points in their travel, as discussed in my co-pending application filed February 5th, 1931, Serial No. 513,690, and all of which are so calculated as to support the load from a certain point below 105 to a certain point above the critical train speed in such manner as positively to preclude the development of excessive vertical jiggle, the combination further including certain initially snubbed units which will give materially increased capac- 110

ity for sustaining the heaviest loads and additionally acting to prevent vertical vibration.

A further object of the invention is to provide a spring assembly having the above pointed out characteristics and in which the only change necessary in the equipment to accommodate the same is the replacement of the ordinary type of truck bolster by one permitting certain of the spring units to extend up thereinto.

10 Another object is to provide a spring assembly in which the number and arrangement of units, or the selection thereof, or the size of the stock from which they are formed, may be varied, depending upon the capacity of the car beneath 15 which the assembly is to be used, it being obvious that greater capacity is needed for cars of the forty, fifty-five and seventy ton type than for those of thirty ton capacity, it being within the purview of the invention to resort to all conceivable modifications requisite for the proper cushioning of cars of various capacities, provided there is no deviation from the underlying principle.

20 A further object is to provide a truck spring assembly in which the units are individual so that certain ones may be interchanged, an added feature being to provide an assembly which will be simple and inexpensive to make and easy to install as well as efficient and durable in service, and a general improvement in the art.

25 To the attainment of the foregoing and other objects and advantages, the invention preferably consists in the details of construction and the arrangement and combination of parts to be hereinafter more fully described and claimed, and 30 illustrated in the accompanying drawings in which:

Figure 1 is a fragmentary elevation, with parts broken away and in section, of a truck side frame having mounted therein a spring assembly constructed in accordance with my invention and supporting the bolster, the bolster being in section and the spring assembly being likewise partially in section on the line 1—1 of Figure 3.

Figure 2 is a vertical sectional view taken on 45 the line 2—2 of Figure 1.

Figure 3 is a diagrammatic plan view with the bolster indicated by dot and dash lines, and

Figure 4 is a diagram showing the working curve of my spring assembly in comparison with 50 the working curves of springs of different types.

Referring more particularly to the drawings, I have shown, generally, a portion of a side frame including the usual compression and tension members 10 and 11 connected by column guides 55 12 defining a window opening 13 for the reception of the bolster 14 supported upon the spring assembly to be described which in turn rests upon the spring seat 15 at the bottom of the window opening. The bolster may be of any ordinary 60 or preferred construction except that the end portion is formed with a longitudinally extending recess 16 for the reception of certain of the spring units to be described. In other respects the bolster may be standard and it is also contemplated that the distance between the bottom 65 surface thereof and the seat 15 accord with the standard or accepted practice.

In carrying out my invention I provide a spring assembly comprising a plurality of units of different characteristics in so far as height, capacity, size and travel are concerned so as to bring about the desired stepped or broken working curve. This assembly in the present instance is shown 70 as comprising a pair of similar units designated 75 as a whole by the numeral 17 and each including

outer and inner coils 18 and 19 of varying pitch, the convolutions of maximum pitch being located at the center and those of the decreased pitch being divided, preferably equally between the two ends, this being resorted to because of the fact that as they have less pitch than the center coils they are under a correspondingly less strain or have a correspondingly less stress and may go solid without danger of breaking at the ends. While dimensions are not to be considered restrictive it is preferable that the outer coils 18 be of 14 and $\frac{1}{8}$ inches free height and approximately 11 and $\frac{1}{8}$ inches solid height and it is on account of this considerable height that the recess 16 is provided in the underside of the bolster to 80 accommodate these units. The inner coils 19 are held under a certain initial compression or snubbed by means of bolts 20 which extend axially through the units and which have enlarged heads 85 21 overlying and constituting abutments for the upper ends of the coils 19. At the bottom of each of these units 17 is an individual spring cap 22 centrally apertured for the passage of the snub bolt 20 which maintains its snubbing relation by virtue of a nut 23 which abuts against 90 the underside of the cap 22. The seat 15 at the bottom of the window opening is necessarily formed with openings 24 accommodating the nuts 23 as will be readily apparent from an inspection of the drawings. A feature of importance is 95 that each snub bolt 20 is provided beneath its head 21 with an enlarged shank 25 fitting comparatively closely within the upper end of the inner coil 19 and is also provided at a point spaced somewhat above the individual cap 22 with an 100 enlargement 26, the enlargements 25 and 26 fitting comparatively closely within the inner coil 19 and serving to center the same. The outer coil 18 of each unit may be considered as centered by its engagement about the inner coil so that 105 relative lateral displacement in any direction will be prevented. The inner coils 19 being snubbed down or held under compression by the bolts 20 have their upper ends below the upper ends of the outer coils 18 and therefore do not 110 come into play until the coils 18 have been depressed to a certain predetermined extent.

I also make use of other units, a pair being shown in the present instance, indicated generally by the numeral 27 arranged between the spring 125 seat and the underside of the bolster. Each of these units includes an outer coil 28 of substantially standard height and having convolutions preferably of uniform pitch. Within each coil 28 is an inner coil 29 of considerably less free 130 height upon which is mounted a follower 30 here disclosed as of cup-like form and containing a coil spring 31 bearing against the underside of the bolster. Each unit 27 may be described as a triple unit inasmuch as in addition to the 135 springs 28, 29 and 31 it includes an innermost spring 32 located within the confines of the spring 29 and held under a certain predetermined degree of initial compression, or snubbed down, by an axially extending bolt 33. Each bolt has its 140 upper end formed with a head 34 overlying the upper end of the spring 32 and snubbing is effected by means of a nut 35. Each of the units 27 has its individual bottom cap 36 centrally apertured for the passage of the bolt 33, the nut 35 engaging against the underside of the disk-like cap. The spring seat 15 is formed with openings 37 for the reception of these nuts. The bolts 33 are similar in connection to the bolts 20 inasmuch as they are formed beneath their heads 145 150

and at their lower portions with enlargements 38 and 39 which fit fairly closely within the springs 32 and which operate to effect centering thereof and to prevent relative displacement laterally of 5 all the coils in each of the units. Clearly the engagement of the nuts 23 and 35 within the openings 24 and 37, respectively, will hold all of the units in the nest in proper position.

Assuming that the nest has been constructed 10 and disposed in the side frame in the proper relation to the bolster as shown and described, it will be seen that the initial load comes upon the outer coils 18 of the units 17 and also upon the outer coils 28 of the units 27. It has been above 15 mentioned that the inner springs 19 of the units 17 are snubbed by means of the bolts 21. It should, however, be noted that they are not both snubbed down, preferably, to the same extent, the one at the right of Figure 2 being shown as 20 snubbed down to a greater extent than the one at the left in the same figure. Actually the inner spring 19 of the unit 17 at the right of Figure 2 is preferably snubbed down so that its normal height will be one inch below the top of the outer 25 coil 18 whereas the inner coil 19 in the unit 17 at the left of the same figure is snubbed down only $\frac{1}{8}$ of an inch. The effect of this is that when the outer coils 18 and 28 are deflected by an increase in the load or as the result of vertical 30 jiggle so that the bolster moves downwardly $\frac{1}{8}$ of an inch the inner coil 19 of the unit 17 at the left of Figure 2 becomes energized. When the springs 18, 28 and the inner spring 19 of the left unit 17, considering Figure 2, are additionally 35 compressed by downward movement of the bolster an additional $\frac{1}{8}$ of an inch the inner coil 19 of the unit 17 at the right of Figure 2 becomes energized. When the bolster moves downwardly 1 and $\frac{1}{8}$ inches the underside thereof will engage 40 against the heads 34 of the bolts 33 and energize the innermost springs 32 of the units 27. When the downward movement is increased an additional $\frac{1}{8}$ inches the underside of the bolster will engage against the followers 13 so 45 that the load will come upon and be yieldingly supported by the intermediate springs 29 of the triple spring units.

The result of the foregoing action is that there 50 will be a series of distinct breaks or steps in the working curve shown in Figure 4. In this graph it will be observed that I have illustrated the performance curve of a spring nest of the Norfolk and Western type, the Dalman type and the A. R. A., all indicated respectively by the numerals 38, 39 and 40, in comparison with the working curve 41 of the present assembly. While again actual figures are not to be construed as restrictive or limitative, I have for the sake of illustration shown a break in the working curve 41 55 at a load of 21,500 pounds and a travel of $\frac{1}{8}$ inches, this being the point where the innermost coil 19 of the snubbed unit 17 at the left of Figure 2 comes into play; a second break at a load of 28,600 pounds and at a travel of one inch, this 60 being the point at which the inner coil 19 of the other unit 17 becomes energized; a third break at a rate of 35,900 pounds and a travel of 1 and $\frac{1}{8}$ inches, this being the point where the snubbed inner springs 32 of the triple coil units become 65 energized; and an additional break or step at a load of 44,000 pounds and a travel of 1 and $\frac{3}{8}$ inches, this being the point where the bolster engages the followers 30 for energizing the springs 29.

Owing to the fact that the increased height

springs 18 and 19 are formed of coils of different pitches, it is clear that such coils will have varying natural periods of vibration so that there will be little danger of building up any vertical jiggle. Furthermore the travel is comparatively slight, only $\frac{1}{8}$ inches, before a snubbing action occurs.

Any tendency of the then energized springs to build up a jiggle will be effectually checked at another $\frac{1}{8}$ inch travel. All of the springs up to this point with the exception of the springs 28 are of varying pitch so that the full benefits of the differences in natural periods of vibration will be obtained. Additional jiggle developing tendencies beyond the point last mentioned will be effectually checked when the springs 32 and 29 come successively into play. The differences between the loads or travels at which the various snubbing actions take place are comparatively slight so that even though there should be a slow acceleration or deceleration rate in a train jiggle at any frequency will not continue for any prolonged time. In this way damage to the car parts and particularly to the lading will be avoided.

The equipment described and shown is intended primarily for use under box cars of fifty-five ton capacity. In the event the spring nest is used for example under a fifty-five ton coal car where the load is always at maximum capacity instead of variable, the number of snubs or steps or breaks in the working curve may be reduced. When the spring assembly is to be used in a forty ton car it may simply be necessary to change the size of the stock from which certain of the units are made, and in case of a thirty ton car a further reduction might be effected. The number of dead-end coils in the variable pitch springs may be varied if necessary so as to maintain the proper travel. For use in seventy ton cars it might be necessary to provide additional springs of standard height similar to the springs 29 located beneath the bolster for providing increased capacity. Other variations might be resorted to without involving any change in the underlying principles.

From the foregoing description and a study of the drawings it is believed that the construction, operation and advantages should be readily apparent to one skilled in the art without further explanation.

While I have shown a preferred embodiment of the invention and have described possible changes it should be understood that the disclosure is merely an exemplification of the principles involved and that the right is reserved to make all such variations and modifications in the construction, the exact combination, the times at which the different elements come into play, as regards load and travel, as will not depart from the spirit or the scope of the claims hereunto appended.

Having thus described the invention, I claim:

1. In a railway car truck, a side frame having a window opening therein, a bolster having its end extending into the window opening, the bolster having its end formed with an upwardly extending recess, and a supporting spring assembly located within the window opening, said assembly including a plurality of springs engaging within said recess and always under compression, 140 other springs located within said first named springs and held under initial compression to be of less height and to become energized subsequent to the energization of the first named springs, and additional springs bearing against the un- 150

derside of the bolster, all of said springs seating at the same level.

2. In a railway car truck, a side frame having a window opening therein, a bolster having its end extending into the window opening, and provided with abutments at different levels, and a supporting spring assembly located within the window opening, said assembly including a plurality of springs engaging against certain of said abutments and always under compression, other springs located within said first named springs and held under initial compression so as to be of less height than the same and to become energized subsequent to the energization of the first named springs, and additional springs bearing against the remaining abutments and enclosing absorption means, all of said springs seating at the same level.

3. In a railway car truck, a side frame having a window opening therein providing a single level seat, a bolster having its end extending into the window opening, the bolster having its end formed with an upwardly extending recess, and a supporting spring assembly located within the window opening, said assembly including a plurality of springs of greater height than the distance between the seat and bolster engaging within said recess and maintained always under compression, other springs of the same free height located within said first named springs and held under initial compression so as to be of less effective height and to become energized subsequent to the energization of the first named springs, and additional springs of less free height than the first springs bearing against the underside of the bolster and enclosing still other springs held under initial compression, all of said springs resting on said single level seat.

4. In a railway car truck, a side frame having a window opening therein, a bolster having its end extending into the window opening, the bolster having its end formed with an upwardly extending recess, and a supporting spring assembly located within the window opening, said assembly including a plurality of springs engaging within said recess and always under compression, other springs located within said first named springs and held under initial compression to be of less height and to become energized subsequent to the energization of the first named springs, additional springs bearing against the underside of the bolster and enclosing still other springs held under initial compression, and a further set of springs of still lower height interposed between said last named springs and the third named springs.

5. In a railway car truck, a side frame having a window opening therein, a bolster having its end extending into the window opening, the bolster having its end formed with an upwardly extending recess, and a supporting spring assembly located within the window opening, said assembly including a plurality of springs having their upper ends seated within said recess, snubbed springs of less height located within said springs, and additional units engaging against the underside of the bolster, said additional units comprising a combination of free and snubbed springs of progressively varying heights.

6. In a railway car truck, a side frame having a window opening therein, a bolster having its end extending into the window opening, the bolster having its end formed with an upwardly extending recess, and a supporting spring assembly located within the window opening, said assem-

bly comprising a unit including free and snubbed springs engaging within the recess, and a unit including a plurality of axially arranged springs engaging against the underside of the bolster, the springs in the second named unit being of varying heights to be successively energized and certain thereof being free and certain being snubbed.

7. A spring assembly for supporting a bolster within a side frame, comprising a plurality of units extending up into a recess in the underside of the bolster, each unit including an outer spring having convolutions of different pitches and an inner spring held under initial compression, and a plurality of units engaging against the underside of the bolster, each of said second named units comprising a snubbed spring surrounded by an additional spring of less free height.

8. In a railway car truck, a side frame having a window opening therein, a bolster having its end extending into the window opening, the bolster having its end formed with an upwardly extending recess, and a supporting spring assembly located within the window opening, said assembly comprising a plurality of units located within the recess and each including an outer coil and an inner coil both having convolutions of different pitches and the inner coil being snubbed, and a plurality of units engaging against the underside of the bolster, each of said second named units comprising an outer coil, an inner coil snubbed down to have less free height than the outer coil and a normally free coil of less free height than the inner coil.

9. A spring assembly for supporting a bolster in a side frame, the bolster being formed in its underside with a recess, comprising a unit located within the window opening and said recess and including outer and inner coils, bolt means extending axially through the inner coil for maintaining the same under initial compression, means on said bolt means for centering the inner coil with respect thereto, and other springs engaging against the underside of the bolster, the side frame being provided at the bottom of the window opening with openings permitting the passage of said bolt means.

10. A spring assembly for supporting a bolster in a side frame, the bolster being formed in its underside with a recess, comprising a unit located within the window opening and said recess and including outer and inner coils, bolt means extending axially through the inner coil for maintaining the same under initial compression, means on said bolt means for centering the inner coil with respect thereto, and other springs engaging against the underside of the bolster, the side frame being provided at the bottom of the window opening with openings permitting the passage of said bolt means, the last named springs comprising the combination of a plurality of concentric coils arranged to become successively energized.

11. A spring assembly for supporting a bolster within a window opening, comprising a spring unit including outer and inner coils, the bolster being provided at its underside with a recess and said outer coil having its upper end engaging against the top wall of the recess, a bolt extending through the inner coil for maintaining the same under initial compression, means on the bolt for centering the inner coil with respect thereto, and the side frame being provided with an opening for the passage of the bolt.
